MECHANICAL PENCIL

Arthur S. Dysart, Onoville, N. Y.

Application February 25, 1936, Serial No. 65,600
Renewed May 23, 1939

8 Claims. (Cl. 120—18)

This invention relates to pencils and particularly to an improved mechanical pencil of the magazine type.

More particularly the invention relates to feeding mechanism for successively advancing lengths of leads from a magazine within the barrel of the pencil successively to their operative or writing position and to adjust the lengths of lead outwardly as they become worn during use.

10 A primary object of the invention is to provide obliquely disposed resilient feeding members in the form of rotatably mounted rollers; these rollers being disposed within the barrel in resilient contact with the inner surface of the barrel, and 15 centrally gripping the lead between them so that rotation of the barrel relative to the supporting member for the rollers will force the lead axially in a direction dependent upon the direction of rotation of the barrel.

20 A feature of importance and by which the axial movement of the lead is accomplished is the provision of three resilient members in the form of rollers within the pencil body adapted to centrally engage the lead, these rollers being 25 mounted for rotation obliquely within an end portion of the pencil and to extend obliquely within and in contact with the barrel of the pencil so that by rotating the barrel the rollers will be simultaneously rotated and revolved by frictional 30 contact with the inner surface of the barrel.

35 A further object of the invention is to provide the feeding rollers of resilient material such as partially vulcanized rubber made in the form of a sleeve or tube and preferably mounted upon a closely wound helical coil of wire so that the rollers may be rotatably mounted upon a central support.

40 Another object of the invention is to provide an elongated eraser extending within the barrel of the pencil and adapted to be advanced positively as it becomes worn away during use, the feeding being effected by rotation of the eraser within the barrel.

45 More generally it is a primary object of the invention to provide an attractive pencil of conventional and convenient size adapted to contain a maximum amount of leads for writing and an ample amount of erasing material, these supplies being housed within the pencil and ready at all 50 times to be immediately advanced into operative writing or erasing position.

55 And finally it is an object of the invention to provide a simple, convenient and easily operated and constructed feeding mechanism for the writing and erasing materials of a mechanical

pencil which will not readily be rendered inoperative.

With the above and other objects in view my invention may include the features of construction and operation set forth in the following specification and illustrated in the following drawing.

In the accompanying drawing annexed hereto and forming a part of this specification, I have shown my invention embodied in complete mechanical magazine pencils with erasers, both the lead and the erasers being adapted to be fed axially as they become worn; but it will be understood that the invention can be otherwise embodied and that the drawing is not to be construed as defining or limiting the scope of the invention, the claims appended to this specification being relied upon for that purpose.

In the drawing:

Fig. 1 is a complete outside view of a pencil, 20 constructed according to the present invention.

Fig. 2 is a longitudinal sectional view of the lead feeding mechanism forming a part of my invention.

Fig. 3 is a corresponding sectional view of the, 25 eraser end of the pencil and the eraser feeding mechanism.

Fig. 4 is a cross sectional view taken upon the plane of line 4—4 of Fig. 2.

Fig. 5 is a cross sectional view taken upon the 30 plane of line 5—5 of Fig. 3.

Fig. 6 is a longitudinal or side view of one of the lead feeding members partly in section and being shown mounted upon its central supporting pin.

35 Fig. 7 is an outside view of a helical spring through which the length of lead passes after being advanced to a point beyond the feeding members.

Fig. 8 is a view similar to Fig. 2 but showing a 40 modified form of the barrel and lead feeding mechanism.

Fig. 9 is a view similar to Fig. 3 but showing a modified form of the eraser.

Fig. 10 is an end view of the parts shown in 45 Fig. 9 and

Fig. 11 is a side view partly in section of the eraser cap shown in Fig. 9.

Briefly, and in its preferred aspect, my invention may include the following principal parts, 50 first, a barrel in which may be placed a number of lengths of lead, and into which may extend also an elongated eraser; second, a sleeve or end portion rotatably and detachably secured relative to the barrel and through which the lengths 55

of lead extend to their writing position; third, a group of rollers rotatably mounted on said sleeve or end portion and resiliently engaging the inside surface of the barrel; fourth, guiding means for a length of lead from the magazine to the forward end of the pencil so that the lead may pass centrally through the barrel and through the group of rollers; fifth, a resilient member engaging and frictionally retaining a length of lead within the end portion after passing the feeding rollers; sixth, an eraser threadedly mounted within an end of the barrel, and seventh, a cap enclosing the eraser and adapted to rotate and advance the eraser as it becomes worn.

Referring more in detail to the figures of the drawing and first to Figs. 1, 2 and 3, I show the pencil as having a pointed end portion 10 and an elongated cylindrical barrel portion 11. Preferably and as shown the rearward portion 12 of the pointed end portion 10 is cylindrical and fits detachably in any suitable manner over the forward end of the barrel 11. The outer surface of this rearward portion 12 may be knurled to facilitate operation of the feeding mechanism by rotating the forward end of the pencil relative to the barrel 11. Frictional contact between these portions may be relied on or means not shown may be employed to retain the front end 10 detachably in position upon the barrel 11. On the forward end of the end portion 10 is a tip 16 preferably threaded on to portion 13 presently to be described.

Fixedly secured within the forward end 10 of the pencil as by being soldered therein is a member 13 having a central axial hole therethrough for the passage of the lead 14. This member 13 at its forward end is provided with screw threads 15 over which may be threaded the point or tip 16 also bored axially for the lead. Within this point or tip 16 is provided a recess housing a closely coiled spring 17 adapted to surround the lead 14. Fig. 7 shows this spring 17 in its unrestrained condition and to be bent laterally at one end so that when mounted in position within the point 16 the spring 17 will bend laterally and frictionally engage against the side of the lead 14 to prevent a short end of a length of lead from dropping from the point 16.

Within the member 13 are secured the forward ends of axis wires or supporting rods 18 for the feed rollers 19. The rearward ends of these rods 18 are made fast within a member 20, freely rotatable within the barrel 11. Rollers 19, three of which may preferably be used, are made up of rubber partially vulcanized and non-oxidizing so that their resilience may be maintained indefinitely. Directly engaging the wires or rods 18 and within the rollers 19 are helically wound coils 21 forming parts of the rollers 19 and over which may be moulded or pressed the rubber portion in the form of a tube. Washers or plates 22 at opposite ends of the rollers 19 are provided forming bearing surfaces for engagement with the adjacent surfaces of members 13 and 20. By means of the springs 21 and the plates 22, friction of the rollers 19 upon the axis wires 18 is reduced to a minimum.

The rollers 19 are not disposed parallelly to the axis of the members 10 and 11 forming the principal parts of the pencil but are disposed obliquely or helically thereto as indicated. Their diameters are such that they will frictionally engage the inner wall of the barrel 11 and be compressed around and firmly grip against the

lead 14, centrally disposed relative to the rollers 19. This frictional engagement of the rollers 19 against the lead 14 serves to hold the lead against slippage rearwardly during operation. By rotating the barrel 11 relative to the front end 10 and the member 13 there will be a small axial component of the rotation of the rollers 19 so that the lead 14 will be slowly advanced or retracted, depending upon the direction of rotation of the barrel 11. By means of this rotation of the barrel 11 the rollers 19 will not only be rotated upon their axes but there will also be a revolving motion of the rollers 19 within the barrel 11 against which they press sufficiently to effect this motion of the lead. 15

Within the barrel in rear of the member 20 is an open or hollow space forming a magazine within which may be placed a number of lengths of lead 14. Member 20 is dished on its rearward face and is provided with a central hole through which a length of lead 14 may pass freely from the magazine within barrel 11 to the space between the feeding rollers 19. Successively as one length of lead is consumed another lead may be advanced as by gravity to the opening within member 20 so that it will be gripped by the rollers 19.

To load the lengths of lead 14 within the magazine it is only necessary to separate the barrel 11 from the end portion 10 and after filling the magazine the end portion 10 may be replaced with the feed rollers 19 and member 20 extending within the barrel.

Forced within the barrel 11 and forming the rear wall of the magazine for the leads is a disk 25. In rear of this disk 25 is ample space for an elongated eraser 26 to be inserted. In Fig. 3 of the drawing is shown a narrow helical ridge forming a screw thread 27, two or three convolutions of this screw thread only being required. The inwardly bent edge of a narrow helically wound strip may be employed to form this screw thread as shown in Fig. 3. Engaging this screw thread 27 is the eraser 26 there preferably being a narrow helical recess cut into the surface of the eraser so that by rotation the eraser 26 may first be inserted within the barrel 11 and thereafter threaded outward as the eraser becomes worn away during use.

In the form of the invention shown in Fig. 3 the eraser is hexangular in cross section and is enclosed within a removable cap or head member 28 fitting over the end of barrel 11 and having a cross section on a portion of its inner surface closely fitting the hexangular form of the eraser. By rotating the member 28 relative to the barrel 11 the eraser 26 may be fed outwardly from the barrel 11 as it may be needed.

In Figs. 9, 10 and 11 is shown a modified form of the eraser end of the pencil. In this form the eraser 30 is cylindrical and is threaded into the same form of screw threads 27 as shown in Fig. 3. In order to thread the eraser 30 outwardly the cap member 31 is provided with a tongue extending centrally within its interior and adapted when in position to enter a narrow opening extending longitudinally within the eraser. The cap member 31 may therefore be used when in position upon the barrel to rotate the eraser and thus feed the eraser outward. 70

In Fig. 8 there is shown a modified form of barrel construction and means for mounting the feeding rollers 19. In this form of the invention the principal parts of the pencil may be two sleeves, the outer one 35 having a point 36 formed 75

thereon through which a lead 14 may extend to writing position. Within this pointed end of the sleeve 35 there may be mounted a helical spring 37 similar in form and operation to spring 17. The feeding rollers 19 instead of being mounted for rotation in a member 13 secured to the end portion 10 are mounted for rotation upon wires or rods the ends of which are secured in spaced members 38 and 40. Member 40 is secured to the end of a tube 41 rotatable within the outer tube or shell 35. The member 39 is freely rotatable within the tapered portion of the sleeve or shell 35. Rollers 19 engage the inner surface of the shell 35 and by rotation of the inner shell 4 relative to this outer shell 35 will be rotated and revolved similarly to the form of the invention shown in Fig. 2.

I claim as my invention:

1. A mechanical pencil comprising in combination a barrel, an end portion rotatable relative thereto and feeding mechanism operatively connected to said end portion and extending into said barrel, said feeding mechanism including a plurality of helically disposed rollers adapted to centrally grip a lead and to rotatably engage the inner surface of said barrel.

2. A mechanical pencil comprising in combination a barrel, an end portion rotatable relative thereto, rollers rotatably mounted in said end portion and disposed obliquely within said barrel, a lead centrally gripped by said rollers, whereby when said barrel is rotated relative to said end portion the lead will be axially advanced.

3. A mechanical pencil comprising in combination a barrel forming a magazine for leads, an end portion rotatable relative thereto supporting feed mechanism for advancing said lead axially within the barrel, guiding means for said lead from said barrel to the point of said end portion, and a group of members within said end portion adapted to centrally and resiliently engage said lead, whereby rotation of said end portion relative to said barrel will axially advance said lead.

4. A mechanical pencil comprising in combination a barrel, an end portion rotatable relative thereto and detachably connected adjacent

one end thereof, rollers obliquely disposed within and engaging said barrel and rotatably secured at one end within said end portion whereby rotation of said barrel relative to said end portion will rotate and revolve said rollers to axially adjacent 5 a lead within the barrel, and means to guide said lead from said magazine to the end of said end portion.

5. A mechanical pencil comprising in combination, a barrel, a sleeve rotatably mounted within said barrel, feeding mechanism operatively connected to said inner sleeve and frictionally engaging said barrel, and guiding means for a lead from said feeding mechanism to its writing position, said feeding mechanism including a group 15 of rotatable members centrally gripping a lead and supporting said lead in alignment with said guiding means and axially of said barrel.

6. A mechanical pencil comprising in combination, a barrel, a feed actuating member rotatable relative thereto, rollers on said feed actuating member resiliently engaging a lead centrally between them and contacting with the inner surface of said barrel, whereby relative rotation of said actuating member and barrel will 25 advance said lead axially.

7. A mechanical pencil comprising in combination, a barrel, an end portion rotatable relative thereto, feeding means for leads within said barrel operatively connected to said end portion and rotatable with rotation of said barrel relative to said end portion, said feeding mechanism including rotatable symmetrically disposed compressible members centrally gripping a length of lead 30 and engaging the inner wall of said end portion.

8. A mechanical pencil comprising in combination, a barrel, feeding mechanism for leads within said barrel relatively rotatable thereto and externally operated, means for rotating said mechanism relative to said barrel, said feeding 40 mechanism including a plurality of helically disposed rollers adapted to centrally grip said lead and to rotatably engage the inner surface of said barrel.

ARTHUR S. DYSART. 45
